Application May 3, 1933, Serial No. 669,086

7 Claims. (Cl. 58—26)

This invention relates to time indicating clocks and more particularly to the type of clocks in which the time indications are read directly from numerical indications.

5 The usual indication of time from a clock is to note the position of a pair of hands relative to a dial on which the only figures appearing are a single set of figures from 1 to 12 inclusive which designate the hour only. The minute hand position is estimated by its relative position to the hour figures and through habit it is quickly determined by a glance at reasonably close approximation to the exact time. One seldom counts the minute marks to determine exactly. The extent of this habit of estimating approximate 10 time is more clearly brought out in a more exaggerated manner by the popular acceptance of the many queer shaped ornamental dials that may be found on time-pieces such as rectangular, 15 oblong dials in which the hands register in only two positions with the indicating marks on the dial's edge, namely, on the opposite ends of the short axis of the dial. The ends of the hands are nowhere near in register with the indications on the long axis of the dial. In many processes and 20 scheduled work it is vitally important that the particular minute can be noted immediately. In railroad work, for example, it is desired to read the time directly in the same terms as printed 25 in the railroad time schedules so that immediate glance at the clock will give the time indication to the minute without the necessity of counting minute marks. It is the general object, therefore, of this invention to provide a time indicating 30 device in which the time is indicated directly by a single set of numerals appearing in the time indicating positions.

Another object is to provide a time indicating device in which the time indications appear on a 35 plurality of endless movable tapes.

Still another object is to provide a time indicating mechanism as set forth in the previous objects, in which the movable tapes are advanced periodically under the control of electrical 40 impulses.

A further object is to provide a time indicating mechanism as set forth in the previous objects, which may be automatically corrected for any divergence from the correct time due to power 45 failure.

Other objects and advantages of this invention will be apparent from the specification and accompanying drawings which show one embodiment of the invention and wherein similar reference numerals indicate similar parts and wherein 50 in the drawings.

Fig. 1 is a perspective view of the time indicating device;

Fig. 2 is a sectional elevation taken substantially on lines 2—2 of Fig. 3;

Fig. 3 is a view of the rear of the machine with the casing removed, looking in the direction of the arrows 3—3 in Fig. 2;

Fig. 4 is an enlarged detail view of the control mechanism;

Fig. 5 is a detail section taken on line 5—5 of Fig. 4;

Fig. 6 is a detail of selected parts of the mechanism, looking in the direction of the arrows 6—6 of Fig. 4;

Fig. 7 is an enlarged detail plan view of one of the contact assemblies;

Fig. 8 is a detail side elevation of one of the control contacts;

Fig. 9 is a section taken substantially along the 15 lines 9—9 of Fig. 2;

Fig. 10 is a circuit diagram showing the wiring circuit for the device; and

Fig. 11 shows the development of the continuous tapes showing the perforations and 20 figures.

The indicating mechanism may be enclosed in any suitable case to harmonize with the surroundings where it may be located. In the present embodiment, a plain rectangular case 20 25 (Fig. 1) is provided, which is adapted to fit into suitable ornamental receptacles. The front of the casing is provided with a plurality of apertures 21 which are provided with glass or other suitable transparent coverings 22 (Fig. 2). The 30 case is mounted on the base 23 and is secured to the front of the supporting frames 24 by means of angle pieces (not shown). The mechanism is mounted on the base and supported by a plurality of supporting plates 26 in the front and a plurality of supporting plates 25 in the back (Figs. 2, 3, and 9). These plates are mounted on the base and are tied together at the top by cross bars 28 (Fig. 2). Mounted on shafts supported by the side bracket 25 are feed rolls 27, 27a, and 40 27b. These feed rolls are free to rotate on their supporting shaft and fixed to one end of the rolls are gears 28, 28a and 28b. Each of these gears drives through identical, separate gear trains to the power shaft so that for the sake of simplicity 45 only one will be explained. The gear 28, meshes with an idler gear 29, rotatably mounted on a shaft fixed to one of the side frames 25 (Figs. 3 and 4). The idler gear 29 meshes with a gear 30 which is mounted on the main power shaft 31. 50 The main power shaft extends clear across the machine and is journaled in the side frames 25. The gear 30 is free to rotate on the main power shaft and has fixed to it a beveled gear 32. This beveled gear meshes with a beveled gear 33 which 55 is rotatably mounted on a stud fixed to a ratchet wheel 34 by means of a mounting bracket 35.

The ratchet wheel 34 is free to rotate on the power shaft by which it is supported. When the power shaft rotates and the ratchet wheel 34 is 60

unobstructed, the beveled gear 32 is held stationary by the resistance of the rollers and the beveled gear 33 rolls around it causing the ratchet wheel 34 to rotate freely.

5 Adjacent and below the ratchet wheel 34 is a member 37 pivotally mounted on a rod 38 extending across the machine and supported by the side brackets. The member 37 is located in the same plane as the ratchet wheel and has an 10 extension 39 adapted to engage the ratchet wheel 34 whenever the member 37 is rotated counterclockwise. This member is normally biased in a clockwise direction by a spring 40 having one end attached thereto and the other end fixed to a 15 mounting plate 25. Another extension 41 of said member is provided with an arcuate notch in which a roller 42 seats. The roller is pivoted between two ears of a U-shaped member 43 which is pivoted at 44 to a bracket 45 mounted 20 on the core of a magnet 46.

The U-shaped member is biased in a counterclockwise direction by a spring 47 attached at one end to an extension 48 of the U-shaped member. This extension abuts an insulated block 49 25 mounted on one of the spring blades of the normally opened contacts 50 which are mounted on, but insulated from, a bracket 51, which in turn is mounted to one of the side frames 25. Pinned within the legs of the U-shaped member 43 is an 30 armature 52 adapted to cooperate with the pole face of the magnet 46. When said magnet is energized and attracts its armature, the member 43 is rocked clockwise and the roller 42 rolls out of the notch in extension 41 camming the member 37 in a counterclockwise direction, thereby bringing the extension 39 into engagement with the ratchet wheel 34 to prevent it from rotating (see Fig. 2). Thus, if the power shaft 31 now rotates, this rotation is transmitted through 40 beveled gears 36, 33, and 32, gears 30, 29, and 28 to the roller 27.

Impinging against the roller 27 are friction rolls 53 pivotally mounted on a bracket 54 which in turn is pivotally mounted on a rod 55 supported 45 by the side frames 25. The rollers 53 are pressed firmly against the roll 27 by virtue of the tension of springs 56 which bias the bracket 54 in a counterclockwise direction, as viewed in Fig. 2.

One end of the springs 56 is anchored to the rod 50 38 and the other end is fastened to the bracket 54.

The side frames 24 on the front of the machine have rotatably mounted thereon rolls 57 and 58 (Fig. 2). There are three sets of these rolls corresponding to the rolls 27, 27a and 27b, which are 55 partially shown in Fig. 9, as 58, 58a and 58b, the upper rolls 57 not being shown. The rolls 27, 57 and 58 are adapted to receive and carry an endless tape 60 of a suitable translucent material. The two other sets of three rolls each are each 60 adapted to carry an endless tape of like material but each set is independent of the other. These three tapes carry the time indicating indicia and are each operated from the power shaft 31 by mechanism identical in detail with that previously 65 described. One of the tapes carries indicia designating the units of minutes; another, the tens of minutes; and the third tape indicates the hour.

The mechanism previously described was for 70 driving the tape carrying the units of minutes. To describe the operation of the other two would be to repeat the description previously given word for word, using the same reference numerals with the suffix "a" for the tens of minute section and 75 the suffix "b" for the hour section. Like refer-

ence numerals with the suffixes added refer to like parts as those already described.

Referring now to Fig. 2, which is a section through the units of minutes section, the tape 60 is carried around the roll 27 into the bite of the roll 27 and the spring-pressed roll 53 through an aperture 61, into a storage well 62, where it lies in folds. From this storage well it passes over the edge and under a baffle plate 63 and out of the storage well through an aperture 64, around 10 the roller 58, past the apertures 21 in the front of the housing, over the roll 57, and back to the roll 27. The storage well 62 is a box-like structure made of suitable sheet metal material and supported rigidly on the base of the machine by 15 tie-straps to the side frames and cross struts such as indicated by the reference numerals 65. The purpose of the storage well is to store the excess tape where it can be fed out conveniently to indicating position. The surface of the tape 20 is covered with an opaque coating with the exception of the area outlined by the different indicia so that illumination placed in back of the tape will pass through the translucent part which shows the indicia in the manner shown in Fig. 1. 25 For this purpose electric lights 66, 66a and 66b are suitably mounted in back of each tape between the cross braces 26.

Referring now to Fig. 11, the three tapes are 30 provided with a series of perforations in a plurality of different alinement for the purpose of controlling the movements of the tapes with respect to the proper alinement relative to the apertures 21. Only one series of perforations 67 are provided in the hour tape 60b, the purpose of 35 which is to control the positioning of the indicia in proper visible registration upon each movement of the tape. The tape 60a carries tens of minute indicia and will hereafter be called the "tens tape". This tape has three series of perforations, 40 68, 69, and 70. The perforation 68 is for effecting transfer from minutes to hours; the perforation 69 is for effecting corrective operations, to be explained later; and the perforation 70 is to control the positioning of the tape in proper 45 registering position.

The tape 60, carrying the units of minutes and indicia, hereinafter to be called the "unit tape" 50 is provided with four series of perforations 71, 72, 73, and 74. The function of the perforation 71 will be explained in detail later and relates to the self-corrective feature. The perforations 72 control the registration position of the unit tape; the perforation 73 controls the transfer from unit to tens of minutes; and the perforation 74 relates to self-correction of the device. The hour tape 60b is provided with twelve evenly spaced numerals 1 to 12, inclusive. The tens tape 60a is provided with twelve evenly spaced indicia 0 to 5 and 0 to 5, inclusive. The repetition of the numerals on the tape is for the purpose of making the tape long enough to go into the machine. The unit tape 60 is provided with ten evenly spaced indicia 0 to 9, inclusive. The ends of each tape are joined together, making three separate endless belts, which are run over the rollers as previously described, with the excess length of tape being stored in folds in the storage well 62.

Referring now to Figs. 2, 8 and 9, a bed plate 70 78 runs transversely across the machine and rests on the base 23. This bed plate underlies all of the tapes. Mounted on the bed plates are a series of blocks 79 adjacent to the edge of the tapes. Pivoted at 80 to these blocks are contact levers 75

81 which are provided with free running rollers or wheels 82 rotatably mounted to the lever by the stud 83. On the same end of the lever and adjacent to the roller wheel 82 is mounted a disk 5 of insulating material 84 which is adapted to cooperate with spring blade contacts. There are eight sets of contacts in the device each one of which is controlled by a contact lever such as described. The contact of the type shown in Fig. 10 opens when cooperating with a perforation and that shown in Fig. 8 closes when cooperating with a perforation.

The roller wheels 82 on the contact levers are each alined with a series of perforations on the 15 tapes and are adapted to drop into these perforations whenever they pass underneath one of the roller wheels. To facilitate this, slots 85 have been milled in the bed plates directly beneath the wheels 82 so that when the perforations pass 20 under the wheels they will drop through the perforations and into the slots thus dropping the contact lever 81 and operating the contact controlled thereby. When the tape moves and the wheel 81 is in the slot, the rolling action of the 25 wheel as the end of the perforation strikes it causes it to roll out of the slot and perforation and onto the surface of the tape.

Turning now to Fig. 3, the motive power for 30 operating the tapes is derived from a driving motor 123 which has a housing 87 integral with the motor casing containing a worm and gear, the worm being fastened to the armature shaft and the worm gear being fixed to shaft 88, to which is also fixed beveled gear 90, fastened to 35 shaft 91 journaled in brackets 92. At the upper end of shaft 91 is fixed a beveled gear 93 which meshes with another beveled gear 94 fixed to the drive shaft 31.

The contacts which control the operation of 40 the tapes are mounted on a cross strip 95 and are insulated therefrom. These contacts comprise contacts 96 controlled by the perforations in the hour tape; contacts 97 and 98 and 99 controlled by perforations in the tens tape, contacts 45 100, 101, 102, and 103 controlled by the perforations in the unit tape (see Figs. 8 and 9).

Turning now to the wiring diagram shown in 50 Fig. 10, the wiring in the present embodiment is arranged to operate the clock on an hourly super-vised system such as is shown in the patent to J. W. Bryce, No. 1,687,491, dated October 16, 1928 in which three wire circuits are run to each of the secondaries, or its equivalent, two wires and a ground return circuit.

55 In the Bryce patent these lines are designated A, B, and C and would be connected to the terminals A, B, and C respectively shown in Fig. 10. The wing and layout of the contacts and relays shown in this diagram are schematic to present 60 an orderly arrangement to simplify the description. The relays including magnets 110, 120 and 130 and the manually operated contacts 140, 140a and 140b may be mounted in any suitable panel box of standard construction, preferably in a 65 readily accessible position for inspection and manual control of the indicating unit. As the indicating unit is most frequently placed in a recess in the wall where it is not readily accessible it is preferred to separate the control units from 70 housing containing the indicating mechanism. Terminals 104 and 105 may be connected to any suitable source of commercial current supply, preferably 110 volts A. C. or D. C. With the clock in operating condition, the switch 106 is 75 normally closed. Minute impulses normally sent

out over the system to which this secondary is attached are received at the terminal A and pass over line 107, through normally closed relay contacts 108, wire 109, relay magnet coil 110, line 111, to terminal C which is the return line, the 5 same as shown in the Bryce patent referred to previously. The energization of coil 110 closes contacts 112 and closes a circuit from one side of the power supply 105, through wire 113, contacts 112, wires 114 and 115, magnet coil 46, wire 10 116, to the other side of the line 104. The energization of magnet 46 closes contact 50, as previously explained and closes a circuit through the motor relay magnet as follows: from supply line 105, through wires 117, 118, contact 50, wire 119, 15 motor relay magnet 120, wire 121, to the other side of the line 104. Relay contacts 122 are now closed completing the circuit through the motor 123, to start it operating, in the following manner: from one side of line 104, through wire 124, 20 motor 123, relay contact 122, wire 117 to the other side of the line 105. The motor now operates to rotate the drive shaft 31 (Fig. 4) and the magnet 46 causes the pawl 39 to engage the ratchet wheel 38 to hold it stationary, thus causing the power shaft to drive the roller 27 and thus drive the tape 60 as previously explained. When the tape is still, some of the perforations 25 in the tape are adjacent some of the contact rollers 84 as shown in Fig. 8 so that the rollers set into these perforations. The roller 84 supporting contact 101 normally sits in its adjacent perforation when the units tape is in registering position and in such position contact 101 is normally open.

30 As the tape 60 moves, as previously explained, the perforation moves out of registering position with its supporting roller causing the roller to ride up onto the surface of the tape and causing contact 101 to close. The minute impulse which causes the tape to move is of about two seconds duration but before this impulse terminates the tape has moved sufficiently to close contact 101, closing a circuit through the magnet 46 as follows: from the supply line 105, through wire 117, contact 101, magnet 46, wire 116, to the other side of the supply line 104. This holds the magnet 46 energized and keeps the units tape 60 moving as long as the contact 101 remains closed. 40 When the next succeeding figure on the units tape reaches registering position, the roller supporting contact 101 encounters another perforation 67 through which it drops causing the contact 101 to open, thus deenergizing magnet 46 causing the 45 pawl 39 to become disengaged from the ratchet wheel 38, thus stopping the tape in registering position. The deenergization of magnet 46 also causes contact 50 to open and stop the motor 123.

50 When the 9 unit on the units tape 60 is in registration position and is to be moved to 0, it is necessary to effect a transfer to the tens numeral and cause the tens tape to register its next succeeding numeral. This is accomplished in the following manner: With the 9 unit in position, the perforation 73 on the unit tape lies immediately in the path of the supporting roll for contact 102. This contact is normally open and is the type shown in Fig. 8. When the minute impulse is received to move this tape from 9 to 0, the tape 65 moves as previously explained and immediately after the movement is initiated the roller supporting contact 102 encounters the perforation and drops into it closing contact 102. This perforation is longer than the others and is designed to 70 75

hold the contacts 102 closed for about two seconds while this perforation passes by.

When this perforation has passed, the roller rolls out on the surface of the tape and contact 5 102 opens and remains open until the tape has again completed an entire cycle to the 9 position. When the contact 102 closes for two seconds, it acts to move the tens tape in exactly the same manner as the minute impulse effects the unit 10 tape. A circuit is completed from one side of the supply line 105, through wire 117, contact 102 (now closed), wire 131, normally closed, contacts 99, magnet 46a, wire 116, to the supply line 104. The magnet 46a thus becomes energized and 15 closes contact 50a across the motor circuit to insure that the motor 123 will continue to operate until the tape 60a is in proper registering position. Perforations in the tape 60a effect control of the contact 99 in the same manner that contacts 101 20 were effected; that is, as soon as the magnet 46a is energized and the tape 60a moves, the contacts 99 close to continue the movement of the tape after contacts 102 open until the next succeeding number on the tape 60a is in registering position 25 when the next perforation is encountered which opens contacts 99 deenergizing magnet 46a and opening contacts 50a stopping the tape 60a and the motor 123. Transfer to the hour tape takes place when the minute tapes changes from the 59 30 position to the 00 position, such as from 11:59 to 12:00 o'clock. This transfer is effected in the same manner in which the previously mentioned transfer was effected. In this instance, the elongated perforation 68 in tape 60a causes contact 35 97 to close momentarily to energize the magnet 46b through the following circuit: from one side of the supply line 105, through wire 117, contact 97 (now closed), wire 125, magnet 46b, wire 116, to the other side of the supply line 104. The 40 magnet 46b closes contact 50b, in like manner to magnets 46 and 46a, to keep the motor operating sufficiently long for the hour tape to be properly positioned. As in the previous instances, when the hour tape starts operating perforations there- 45 in cause contacts 96 to close to maintain the circuit through the magnet 46b until the hour tape has reached its proper registering location. Contacts 140, 140a and 140b are manually operable for the manual operation of the tapes 60, 60a and 50 60b, respectively, when any one or all of these tapes require adjusting or correcting such as the advance in time when changing from standard time to daylight saving time. The closing of contact 140 completes a circuit from one side of the 55 line 105, through switch 106, line 117, contact 140, line 115, magnet 46, line 116 to the other side of the line 104. The energization of magnet 46 causes the tape 60 to be moved as previously described. Similarly, the closure of contacts 140a 60 and 140b causes the magnets 46a and 46b, respectively to be energized.

The operation of the device as described thus far is adapted to operate on any minute impulse electric time system. To adapt the device to be 65 operated on an hourly supervised system, such as shown in the Bryce Patent No. 1,687,491, the additional perforations previously referred to are required in the units and tens tape as well as additional contacts cooperating therewith and 70 additional circuits. As shown and described in the Bryce patent, rapid supervising impulses are periodically sent over the A wire, and normal impulses are sent over the B wire only during a certain period of the hour, the B wire remaining 75 dead at other times. The rapid impulses are

sent over the line between the 59th and 60th minutes. If the time indicating device is in correct time with the controlling master clock when said master clock reaches the 59th position, the units and tens tape will indicate 59 and a perforation 74 in the units tape will cooperate with the roller of contacts 103 causing said contacts to close, also a perforation 69 in the tens tape will cooperate with the roller supporting contacts 98 causing them to close. The closure of contacts 103 and 98, which are wired in series, establishes the following circuit: from one side of the power supply 104, through wire 116, contact 103, now closed, wire 128, contacts 98, now closed, wire 129, resistance unit 130, relay magnet coil 131, wires 132 and 117, back to the other side of the power supply 105. The relay coil 131 now being energized, attracts its armature and causes contacts 108 to open and contacts 133 and 134 to close. The opening of contacts 108 and closure of contacts 133, transfers the magnet 110 from the A wire to the B wire. Rapid impulses coming over the A wire about ten seconds after the 59th minute impulse are not, therefore transmitted to the coil 110 and therefore the time indicating device is unaffected. Should the time indicating device be slow, the perforations 69 and 74 would not be in their proper controlling position so that contact 108 would still remain closed and the rapid impulses would flow through to the indicating device advancing it, until it reached the 59th minute at which time contact 108 would open and prevent any more rapid impulses from affecting it.

The closing of relay contact 134 completes a holding circuit through the relay coil 131 as follows: from one side of the power supply 104, through wires 116 and 135, contacts 134, resistance unit 130, relay magnet coil 131, wires 132 and 117, and back to the other side of the power supply line 105. The rapid impulses being transmitted over the A wire cease shortly before the 60th minute impulse is transmitted, and then the 60th minute impulse is transmitted over the B wire, in accordance with the description in the Bryce patent previously mentioned. The 60th minute impulse, therefore, energizes the relay coil 110 as follows: from the B wire terminal through contacts 133, now closed, wire 109, relay magnet 110, wire 111 to the common return C. The operation of the relay coil 110 and its corresponding contact 112, then step the unit and tens tapes along one position as previously explained, thereby removing the perforations 74 and 60 69 from cooperation with their corresponding contacts 103 and 98 causing both of these contacts to open. The holding circuit through magnet 131, however, continues to hold contacts 133 closed and regular minute impulses still continue to be transmitted over both the A and B lines until about 44 minutes after the hour at which time the minute impulses cease to be transmitted over the B wire until the next succeeding 60th minute impulse. When the time indicating device indicates 4 minutes after the hour, a perforation 71 in the units tape engages the rolls supporting contact 100 causing said contact to close. This closes the following shunt circuit around the magnet coil 131 to deenergize it: from one side of the supply line 105, wire 117, contact 100, now closed, wire 136, resistance unit 130, contact 134, now closed, wires 135 and 116 to the other side of the supply line 104. With the deenergization of magnet 131, contact 134 opens 65 breaking the holding circuit and the shunt cir- 70 75 75

cuit, and contacts 133 open and contacts 108 close thus transferring the time indicating device from the B line back to the A line.

In event that the time indicating device is 15 minutes or less fast, the tens and units tapes will reach the 59th minute position in advance of the master clock controlling the system and will cause said device to be transferred to the B wire which is dead, between the 44th and 60th chronological position of the master clock. The indicating device will accordingly be stopped at its 59th chronological position until the master clock sends the first impulse over the B wire on the 60th minute which will then advance the time indicating device in step with the controlling master clock.

While the novel features of the invention have been shown and described as applied to a single modification, it will be understood that various omissions and substitutions and changes in the form and details of the device illustrated and in its operation may be made by those skilled in the art without departing from the spirit of the invention. I intend to be limited therefore only 25 as indicated by the scope of the following claims.

I claim:

1. A time indicating device having a plurality of circuits adapted to receive normal periodic electrical impulses and rapid electrical impulses, comprising movable indicia bearing elements for indicating time, a motor for driving said elements, means controlled by normal and rapid electrical impulses for initiating operation of said motor, and means controlled by the position of said indicia bearing elements for terminating the operation of said motor.

2. A time indicating device having a plurality of circuits adapted to receive normal periodic electrical impulses and electrical impulses more rapid than normal, comprising movable indicia bearing elements for indicating time, a motor for driving said elements, a releasable driving train between said motor and said elements, means operable by normal and rapid electrical impulses for controlling said driving train, and means controlled by the chronological position of said time elements to determine whether said first named means shall be operated by said normal or rapid impulses.

3. In combination a time indicating device having a series of denominational order indicating elements arranged side by side to jointly indicate the time of day, a motor, releasable driving mechanisms between said motor and each of said elements to independently drive the same, electro-magnetic means for controlling the operation of each of said driving mechanisms, electrical contacts controlled by the element of a lower denominational order for controlling the electro magnetic means associated with the next higher denominational order element to render its associated driving mechanism effective to drive said last mentioned element, additional electrical contacts associated with each denominational order element for controlling the electro-magnetic means associated with said element to render its associated driving mechanism ineffective to terminate the drive of said element, and circuits connecting said electrical contacts and said electro-magnetic means.

4. In combination, a time indicating device having a series of denominational order indicat-

ing elements arranged side by side to jointly indicate the time of day, a motor, releasable driving mechanisms between said motor and each of said elements to independently drive the same, periodically operated time controlled means for controlling the driving mechanism associated with the element of lowest denominational order and for initiating operation of said motor to effect periodic operation of the same, and additional means controlled by each element of a lower denominational order for controlling the driving mechanism associated with the element of the next higher denominational order to effect periodic movement thereof, said last named means including means rendered effective by the operation thereof for controlling said motor.

5. A time indicating device having a plurality of time indicating elements of different denominational orders arranged side by side to jointly indicate the time of day, a motor, differential gear trains connecting said motor with each of said elements, electro-magnetic means for controlling each of said differential gear trains for effecting operation of its associated element, time controlled electric contacts for effecting operation of one of said electro-magnetic means to initiate periodic operation of the element of the lowest denominational order, electric contacts controlled by each element of a lower denominational order for controlling the electro-magnetic means associated with the element of the next higher denominational order to effect operation thereof and circuits connecting said electric contacts with said electro-magnetic means.

6. A timing device comprising a plurality of indicia-bearing elements for indicating time, each element having a different denominational order, a motor for driving said elements, releasable driving trains between said motor and each of said elements, electromagnetic means associated with each of said releasable driving trains to render said driving means effective, said elements having apertures arranged in spaced relation, and means cooperating with said apertures for selecting the electro-magnetic means to render effective the releasable driving means associated with the element of a higher denominational order to operate said element.

7. In combination, a time indicating device having a series of denominational order indicating elements arranged side by side to jointly indicate the time of day, a motor, releasable driving means between each element and said motor, periodically operated time controlled means for controlling the driving mechanism associated with the element of lowest denominational order for rendering said driving mechanism effective, means operable by said time controlled means for initiating operation of the motor to move said time indicating element, means for controlling the driving mechanism associated with the element of the next higher denominational order, means operated by the subsequent movement of the element of the lower denominational order for operating the driving mechanism control means associated with the time indicating element of the next higher denominational element and means controlled by the subsequent movement of said last named time indicating element for controlling the operation of the motor for a predetermined period.
